His Attorney.

UNITED STATES PATENT OFFICE

163,257

COIN-ACTUATED AUTOMATIC PHONO-
GRAPH APPARATUS

Edward J. Collins, Los Angeles, Calif., assignor to
Williams Manufacturing Company, Chicago,
Ill., a corporation of Illinois

Application December 1, 1950, Serial No. 13,231

Term of patent 3½ years

(Cl. D56—4)

To all whom it may concern:

Be it known that I, Edward J. Collins, a citizen of the United States and a resident of Los Angeles, in the county of Los Angeles and State of California, have invented a new, original, and ornamental Design for a Coin-Actuated Automatic Phonograph Apparatus, of which the following is a specification, reference being had to the accompanying drawing, forming a part thereof, and in which the single figure is a perspective view of a coin-actuated automatic phonograph apparatus, showing my new design. The back of the cabinet is plain, and both sides are substantially the same.

I claim:

The ornamental design for a coin-actuated automatic phonograph apparatus, as shown and described.

EDWARD J. COLLINS.
